Attorney

UNITED STATES PATENT OFFICE.

JAMES KENT CARSKADDON, OF PEARSON, WASHINGTON.

MUFFLE FURNACE.

Application filed June 18, 1921. Serial No. 478,481.

To all whom it may concern:

Be it known that I, JAMES K. CARSKADDON, a citizen of the United States of America, and resident of the town of Pearson, in the 5 county of Kitsap and State of Washington, have invented certain new and useful Improvements in Muffle Furnaces, of which the following is a specification.

My invention relates to muffle furnaces 10 and particularly to a muffle furnace of a small size, such as is suited to baking of teeth, which is a frequent job in dental offices.

The object of my invention is to provide 15 an effective small furnace suited to this type of use which will be cheap in construction and which will be durable and have long life.

The features of my invention upon which 20 I desire to obtain a patent will be herein-after described and then particularly defined by the claims.

The accompanying drawings show my invention embodied in the type of construction 25 which I now most prefer to use.

Figure 1 is a longitudinal section through the axis of the furnace.

Figure 2 is an end elevation of the furnace, taken from the side opposite that at which 30 the gas is applied thereto.

Figure 3 is a section taken upon the line 3-3 of Figure 1.

This furnace has an outer shell, an inner muffle case, and a muffle which is designed 35 for removable insertion in the muffle casing. The main body of the outer shell consists of a tubular shell 1 which is composed of some suitable refractory material such for instance, as fire clay. To prevent crack- 40 ing of this under heat, I have provided the same with a slit, as 10, extending length- wise thereof. This permits free expansion and contraction without producing undue strains within the body of the shell.

45 The ends of the main shell 1 are closed by two end plates 2 and 3. These are each provided with openings somewhere adjacent to or just above the center thereof for the reception of the muffle, for the entrance of

50 the heating gas and for the escape of the hot gases. These end plates, which close the shell 1, are also provided each with a slot, as 20, extending from the opening for the muffle to the outer edge thereof. The pur- 55 pose of this is also to relieve the plate from

the internal strains caused by heating and cooling and prevent its cracking elsewhere.

Within the chamber formed by the tubular shell 1 and the two end plates, is placed the muffle casing 4. This muffle casing has 60 one end enlarged by the downward slope and inclination of the floor thereof, as is shown at 40 in Figure 1. This is placed toward the end of the furnace at which the heated gas is introduced. The upper side 65 of this muffle casing may be slit, as shown at 42, to permit expansion and contraction, as in the case of the outer shell 1.

At B is shown a conventional representation of a gas burner. This is placed so 70 as to discharge its jet into the opening 30 in the plate 3, this being positioned also so as to discharge the flame upon the downwardly curved floor section 40 of the muffle casing and thus under the muffle. This will 75 result in heating the floor of the muffle casing and in deflecting the heat upwardly toward the muffle 5. The opening 30 in the end plate 3 may be of any suitable shape and of a size which will permit satisfactory 80 entrance to the flame and the air which is associated therewith. The hole in the opposite end plate 2 is made of an irregular shape, which is best shown in Figure 2. This consists of an opening of a size to 85 rather closely fit the end of the muffle 5, modified by external projections or lobes, as 21, which form gas escape passages outside of the muffle. One end of the muffle, the same being the open end, is made of 90 a shape and size to fit within this opening in the plate 2 and be supported thereby. The muffle is also provided with a lug, as 50, projecting from its bottom and engaging with the floor of the muffle casing 4, so as to 95 assist in the support of the muffle. By reason of the engagement of the open end of the muffle with the walls of the opening in the plate 2 and the support of the inner part thereof by the lug 50, the muffle 100 is supported with its walls spaced away from the casing 4 and the gases, therefore, have free opportunity to circulate about the same.

The end of the muffle casing 4 which is 105 towards the discharge end of the furnace, is cut backward on an incline, as is shown at 41. This forms a communication between the chamber within the muffle casing and its surrounding chamber. The end plate 2 also 110

has a ledge 22 projecting inwardly in such position as to form a support for that end of the muffle casing. The other end of the muffle casing may be extended so as to be supported from the lower portion of the tubular shell 1.

I prefer to enclose the outer shell 1 with a layer, as 6, of asbestos or other heat insulating material and the whole is bound together by a sheet, 7, of sheet metal, the ends of which are crimped over sufficiently to hold the end plates 2 and 3 in position and the ends of said plate 7 being of sufficient length to be joined together and secured as by bolts 70 and to then be flared outward, as shown at 71, to form a base or legs for supporting the same.

The above construction of furnace is one which is easily made and quite simple. The slotting of the tubular casing 1 and the muffle shell 4 lengthwise relieves them from internal strain to such an extent that they are not likely to crack. It is therefore possible to use them many times in succession. The muffle 5 is intended to be removed as desired. The opening in the end disk 2 through which the muffle is inserted is provided with a downwardly extending lobe 21, so positioned as to pass the lug 50.

What I claim as my invention is:

1. A muffle furnace having a muffle casing which is slit lengthwise along one side.
2. A muffle furnace having a muffle casing having its lower side inclined downward at the flame receiving end and slit lengthwise along its top.
3. A muffle furnace having a muffle casing having its floor inclined downward at the flame receiving end, its opposite end inclined backward towards its top, and its upper side slit lengthwise.
4. A muffle furnace having a refractory outer tube which is slit lengthwise, end

plates forming closures for said tube and provided with muffle receiving openings and at one side slit from said opening to its periphery, a muffle casing fitting within said tube and having one end enlarged by a downward inclination of its floor, and a muffle having an end having supporting engagement with one end plate and a supporting lug extending between muffle and muffle casing.

5. A muffle furnace having a cylindrical shell, end closing plates having muffle openings and slit at one side from said opening to its outer edge, a muffle casing having its floor at one end inclined downward and lengthwise slit along its upper side, the end plate at the other end having a ledge for supporting the muffle casing, a muffle having its open end fitting in and supported from the walls of the opening in the end plate and a lug engaging the floor of the muffle casing, said opening in the end plate having outward extensions for discharge of gas.

6. A muffle furnace having an outer shell which is slit lengthwise along one side.

7. A muffle furnace having an outer shell slit lengthwise along one side, and a muffle casing supported therein and likewise slit lengthwise along one side.

8. A muffle furnace having an outer shell slit lengthwise along one side, and a muffle casing supported therein and having its lower side inclined downward at the flame receiving end.

9. A muffle furnace having an outer shell which is slit lengthwise along one side, and end plates forming closures for said shell and provided with muffle receiving openings, and at one side slit from said opening to its periphery.

Signed at Seattle, King County, Washington, this 10th day of June, 1921.

JAMES KENT CARSKADDON.
